UNITED STATES PATENT OFFICE.

HARVE R. STUART, OF WHEELING, WEST VIRGINIA.

TELEPHONE RECEIVER.

977,981.

Specification of Letters Patent.

Patented Dec. 6, 1910.

Application filed March 21, 1908. Serial No. 422,397.

To all whom it may concern:

Be it known that I, HARVE R. STUART, a citizen of the United States, residing at Wheeling, in the county of Ohio and State of West Virginia, have invented certain new and useful Improvements in Telephone Receivers, of which the following is a full, clear, and exact description.

My invention relates to telephone receivers for general use in telephonic circuits, and more particularly designed for use in connection with telephones, and has for its object the production of a receiver characterized by improved features of mechanical construction and magnetic parts so arranged and combined mechanically and magnetically as to produce a receiver sensitive to feeble or small currents and capable of producing strong acoustic effects.

My invention consists in the features hereinafter described and claimed.

Reference is hereby made to the accompanying drawing, in which the same reference numerals are used to designate corresponding parts in the several views, of which—

Figure 1 is a plan of the lower half of the receiver with the diaphragm removed, showing the shape of the lower magnet and its supporting casing; Fig. 2 is a section of the complete device on line 2—2 of Fig. 1; Fig. 3 is a side elevation of the receiver; Fig. 4 is a sectional detail of one of the binding posts and a portion of the casing; Fig. 5 is a plan of the lower half of a modified form of receiver with the diaphragm removed; and Fig. 6 is a section on line 6—6 of Fig. 5.

The receiver shown comprises a casing formed of the oppositely disposed cup-shaped members 2 and 3, of non-magnetic material, having horizontal flanges 4 and 5, respectively which are held together by securing screws 6, the diaphragm 7 of magnetic material such as iron being clamped between said flanges 4 and 5, and firmly held thereby. The members 2 and 3 are each provided with a sound conveying tube 8, to which ear pieces, megaphones or listening tubes may be applied. The members 2 and 3 are provided with magnets 9 and 10 respectively and which are preferably permanent magnets, although electromagnets may be used if desired. These magnets are of peculiar shape, shown clearly in Fig. 1, be-

ing in the form of a ring with inwardly extending arms 11, carrying the pole pieces 12 which extend in a direction perpendicular to the plane of the ring. While the ring-shaped magnets are preferably circular in outline, I contemplate the use of other forms of "ring" by which I mean a closed figure of any form. Surrounding the pole pieces are the coils 13, through which the voice currents pass. The magnets 9 and 10 are preferably so disposed as to bring like poles opposite each other, that is, the N pole of magnet 9 is opposite the N pole of magnet 10, but may be disposed so as to bring unlike poles opposite each other, or the plane of the pole pieces of one magnet may be at right angles to the plane of the pole pieces of the other magnet. In each case, the coils 13 are so wound that a current passing through the same in one direction tends to weaken the field of one of the magnets, and at the same time to strengthen the field of the other magnet, whereby the diaphragm 7 is moved toward the magnet whose field is strengthened; when a current passes through the coils 13 in the opposite direction, the diaphragm will be attracted or moved toward the other magnet. The receiver is therefore a balanced receiver, since the diaphragm or armature is normally attracted by magnets of substantially equal strength acting in opposite directions, the voice currents strengthening one magnet and simultaneously weakening the other magnet in alternation.

The magnets 9 and 10 are secured to the casing members by screws 14, rings 15 of yielding or resilient material such as soft rubber, being preferably interposed between the magnets and the casing, so that the length of the air gap between the pole pieces and diaphragm may be increased by tightening the screws 14 to compress the said rings. The casing is divided by the diaphragm 7 into two resonance chambers 16 and 17, with in which the magnets are situated, and which are in unobstructed communication with the sound-conveying tubes 8. The four coils 13 may be connected together either in series or in multiple or in series-multiple as desired. The current may be applied to the windings of the coils from binding posts of any suitable form, that shown consisting of a headed bolt 18 which passes through insu-

lating bushings 19 and 20, which are clamped to the casing by the nut 21, threaded on said bolt. A conducting plate 22, also surrounds said bolt 18 and is rigidly held thereby, said plate being provided with a binding screw 23 threaded therein.

In the modification illustrated in Figs. 5 and 6, each of the magnets comprises a plate 24, which is secured by screws 25 to the cup-shaped members 2 and 3 respectively, which are of non-magnetic material. The said plates 24 have inwardly extending arms 26 to which is secured a plate 27 by screws (not shown) and to the center of said plate is secured a pole piece 28 which extends at right angles to the plane of the plate 24 with its free end in proximity to the center of the diaphragm 7. A coil 29 surrounds the pole piece 28 and is connected with the binding posts 30 for receiving the voice currents and varying the flux of the magnetic circuit. Each magnet also comprises a pair of curved plates 31 disposed opposite each other and secured to the edges of the plates 24. The edges of said curved plates make contact with the diaphragm 7, when the casing members 2 and 3 are secured together by the bolts 6. (See Fig. 3). In this construction, the diaphragm forms a part of the magnetic circuit, the lines of force passing through the same from its center toward its periphery, or vice-versa. The pole pieces 28 of the two magnets are preferably of the same polarity, and the coils 29 are so wound that a current flowing in one direction tends to weaken the magnetic flux of one of the magnets, at the same time strengthening the flux of the other magnet, and a current in the opposite direction strengthens the flux of the first magnet and weakens that of the second. This receiver is also a balanced receiver, as explained in connection with the receiver of Figs. 1-4, and is small, light and compact.

Having now described my invention, what I claim, is:—

1. In a receiver, a diaphragm a pair of magnets each in the form of a ring having inwardly extending filleted arms, and pole pieces extending from said arms transversely to the plane of the ring, the pole pieces of one magnet being opposite the pole pieces of the other magnet; adjacent pole pieces of the two magnets being of similar polarity and disposed upon opposite sides of said diaphragm.

2. In a receiver, a pair of magnets each in the form of a ring having inwardly extending arms, pole pieces extending from said arms transversely to the plane of the ring, the pole pieces of one magnet being opposite the pole pieces of the other magnet and adjacent pole pieces of the two magnets being of similar polarity, and a diaphragm situated between the pole pieces of one magnet and the pole pieces of the other magnet.

3. In a receiver, the combination of a hollow casing, a diaphragm secured thereto, a magnet having a pole in proximity to the center of the diaphragm, a second magnet having a pole in proximity to the center of the opposite face of the diaphragm, a resilient member interposed between each of said magnets and the casing, and means for compressing said resilient means for varying the length of the air gap between each magnet and the diaphragm.

4. In a receiver, the combination of a hollow casing, a diaphragm secured thereto, a magnet having a pole in proximity to the center of the diaphragm, a second magnet having a pole in proximity to the center of the opposite face of the diaphragm, a member interposed between each of said magnets and the casing, and means for actuating said member for varying the length of the air gap between each magnet and the diaphragm.

5. In a receiver, the combination of a cup-shaped casing member having a central sound orifice, a magnet within said member and comprising a flat plate having openings therethrough, a resilient ring interposed between said magnet and said casing member, and means for drawing said magnet and casing member together.

6. In a receiver, the combination of a hollow casing, a diaphragm extending across the same so as to form a pair of sound chambers, each of which has a sound orifice, and a magnet situated within each of said sound chambers and having a pole in proximity to the center of the diaphragm, said magnets being of such a strength and distance from the diaphragm that their attractions are normally balanced, whereby the diaphragm is practically unstressed.

7. In a receiver, the combination of a hollow casing, a diaphragm secured therein and dividing said casing into two sound chambers, each of which has a sound orifice, magnets each comprising a flat plate and a pole piece extending at right angles thereto into proximity to the center of the diaphragm, said magnets being of such a strength and distance from the diaphragm that their attractions are normally balanced, whereby the diaphragm is practically unstressed.

8. In a receiver, the combination of a hollow casing, a diaphragm secured therein to form a sound chamber having a sound orifice, a magnet comprising a flat plate and a pole piece extending at right angles thereto into proximity to the center of the diaphragm, and means for adjusting said magnet toward and away from said diaphragm and a similar magnet arranged close to the opposite face of the diaphragm at such a distance that the attraction thereof balances the attraction of said first magnet.

9. In a receiver, the combination of a simple diaphragm, free from connection with

other vibrating parts, a magnet having its respective poles adjacent to one face of said diaphragm near the center thereof, and another magnet having its respective poles sufficiently close to the opposite side of said diaphragm, near the center thereof, to balance the attraction of the magnet first mentioned, the two magnets being arranged

so that their respective like poles are opposite each other.

10

In witness whereof, I subscribe my signature, in the presence of two witnesses:

HARVE R. STUART.
